[57] **CLAIM**

The ornamental design for a magnet for the treatment of liquids or the like, substantially as shown and described.

DESCRIPTION

FIG. 1 is a front perspective view of a magnet for the treatment of liquids or the like showing my new design;

FIG. 2 is a rear perspective view thereof;

FIG. 3 is an enlarged rear elevational view thereof;

FIG. 4 is an enlarged left side elevational view thereof,

the right side elevational view being a mirror image of

the view of FIG. 4; and

FIG. 5 is an enlarged top plan view thereof, the bottom

plan view being a mirror image of the view of FIG. 5.
